UNITED STATES PATENT OFFICE.

HUGO S. HASSELQUIST, OF CHICAGO, ILLINOIS.

DESIGN FOR A PENCIL.

Application filed July 7, 1922. Serial No. 2,984. Term of patent 3½ years.

To all whom it may concern:

Be it known that I, HUGO S. HASSELQUIST, a citizen of the United States, residing at Chicago, in the county of Cook and State of Illinois, have invented a new, original, and ornamental Design for a Pencil, of which the following is a specification, reference being had to the accompanying drawing, forming a part thereof.

The figure is a side view of a pencil showing my new design.

I claim:

The ornamental design for a pencil, as shown.

HUGO S. HASSELQUIST.
